UNITED STATES PATENT OFFICE.

BENJAMIN I. JOHNSON, OF GASCOYNE, NORTH DAKOTA.

SPARK-PLUG.

1,312,850.

Specification of Letters Patent.

Patented Aug. 12, 1919.

Application filed October 31, 1918. Serial No. 260,474.

To all whom it may concern:

Be it known that I, BENJAMIN I. JOHNSON, a citizen of the United States, residing at Gascoyne, in the county of Bowman, State of North Dakota, have invented a new and useful Spark-Plug; and I do hereby declare the following to be a full, clear, and exact description of the invention, such as will enable others skilled in the art to which it applies to make and use the same.

This invention relates to an improved spark plug particularly designed for use in connection with internal combustion engines, for igniting the charge.

One of the objects of the invention is to provide an improved spark plug having an electrode constructed from a high strength steel.

A further object of the invention is to provide the lower end of the electrode with a metallic nut constructed of any suitable non-corrosive metal preferably brass provided with a terminal to coöperate with an adjacent sparking terminal, so as to create a jump spark from one to the other.

A further object of the invention is to provide a small copper washer for the lower end of the electrode.

A further object of the invention is to provide a copper washer asbestos covered for the upper end of a porcelain filler of the lower end of the spark plug casing.

A further object of the invention is the provision of an upper wood fiber holder and a lower porcelain holder for the electrode, there being an insulation of mica partially telescoping the adjacent ends of the wood fiber holder and porcelain holder.

A further object of the invention is the provision of means for holding the electrode in different adjusted positions.

A further object of the invention is to provide a casing, having means on its interior, for limiting or holding the holders for the electrode in spaced relations to each other.

In practical fields the details of construction may necessitate alterations falling within the scope of what is claimed.

The invention comprises further features and combination of parts as hereinafter set forth shown in the drawings and claimed.

In the drawings:—

Figure 1 is a view in side elevation of the spark plug.

Fig. 2 is a vertical sectional view of the same.

Fig. 3 is a plan view of the spark plug.

Fig. 4 is a sectional view on line 4—4 of Fig. 2.

Referring more especially to the drawings 1 designates a casing of the spark plug, which is exteriorly threaded as shown at 2, so as to be threaded into the end of the cylinder casing. The interior of the casing is 65 provided with annular shoulders 3 and 4, and mounted in the casing 1 are electrode holders 5 and 6. The holder 5 is constructed of wood fiber, and its reduced portion 6 telescopes into the casing 1, so that the shoulder 7 may engage the marginal edge of the flange 8. The holder 5 has a second reduced part 9, engaging the main portion of the bore 10 of said casing, so that the shoulder 11 intermediate the portions 6 and 9 70 may engage the shoulder 3. The electrode 12, which may be constructed of any suitable material preferably soft copper or the like is mounted in the bore 13 of the holder 5. The lower end of the bore 13 of the holder 5 75 flares outwardly as shown at 14. The holder 6 has a reduced portion 15 fitting the main portion of the bore 10 of the casing 1. The holder 6 has a shoulder 16 and interposed between the shoulders 4 and 16 is a suitable 80 washer 17 constructed of any suitable material preferably copper and covered with asbestos. The upper part of the bore 18 of the holder 6 (which is constructed of any suitable material preferably porcelain) 85 flares outwardly as shown at 19. Surrounding the electrode 12 is a filler 20 constructed of any suitable insulating material preferably mica. This filler is tapered toward both ends, so as to fit as shown into the outwardly flared portions 14 and 19 of the bores 13 and 18 respectively. The holder 6 at the lower end of the bore 18 has countersunk therein a tubular washer or sleeve 21 90 constructed of any suitable material preferably of copper. The lower end of the electrode has an enlargement 22 contacting with the sleeve 21, and the sleeve 21 being countersunk into the holder 6, the holder is supported in the casing 1. Projecting from the lower portion of the casing 1 is a sparking terminal 23, and 24 denotes a curved terminal carried by the enlargement 22. The terminal 24 extends toward the terminal 23 and both terminals are designed to be platinum 110

covered, to avoid corrosion, which is otherwise due from constant sparking from one to the other. The upper part of the electrode 12 is threaded, and threaded on the electrode 5 is a nut 25 and a lock thumb nut 26, between which nuts a lead or wire, from a suitable timer or commutator (not shown) may be connected. A washer 27 is mounted on the electrode in contact with the holder 5, and interposed between the nut 25 and the washer 27 is a split washer 28, the ends of which are offset from each other, and by tightening up on the nut 25, steady pressure is yieldably exerted to hold the shoulders 3 and 11 in contact, and the washer 17 between the shoulders 4 and 16.

The invention having been set forth what is claimed as new and useful is:—

In combination with a spark plug casing having interior concentric shoulders, of inner and outer porcelain and fiber holders telescoping said casing and engaging said shoulders, said holders having axially alined

bores having their adjacent ends flared outwardly a copper sleeve countersunk in the lower end of the lower holder, an electrode of soft copper extending through the holders and having an enlargement contacting with the copper sleeve, and means on the upper part of the electrode for drawing the aforesaid parts together, a washer between a shoulder of the lower holder and one of the shoulders of the casing, a filler surrounding the electrode and having its opposite ends telescoping into the flared out portions of the holders, the lower part of the casing and the enlargement of the electrode having coöperating sparking terminals.

In testimony whereof I have signed my name to this specification in the presence of two subscribing witnesses.

BENJAMIN I. JOHNSON.
